[57] CLAIM

The ornamental design for a tool for coring and cutting, as shown and described.

DESCRIPTION

FIG. 1 is a perspective view of a tool for coring and cutting, showing my new design;

FIG. 2 is a side view thereof;

FIG. 3 is a top view thereof;

FIG. 4 is a rear view thereof;

FIG. 5 is a front view thereof;

FIG. 6 is a bottom view thereof;

FIG. 7 is a perspective view of a second embodiment of FIG. 1;

FIG. 8 is a side view of FIG. 7;

FIG. 9 is a top view of FIG. 7;

FIG. 10 is a rear view of FIG. 7;

FIG. 11 is a front view of FIG. 7;

FIG. 12 is a bottom view of FIG. 7;

FIG. 13 is a cross-sectional view taken along line 13-13 of FIG. 3; and,

FIG. 14 is a cross-sectional view taken along line 14—14 of FIG. 9.
